By
R. S. Bunn,
Attorney.

UNITED STATES PATENT OFFICE.

WILLIAM F. MASON, OF LOS ANGELES, CALIFORNIA.

TABLE.

1,407,039.

Specification of Letters Patent. Patented Feb. 21, 1922.

Application filed June 17, 1920. Serial No. 389,720.

To all whom it may concern:

Be it known that I, WILLIAM F. MASON, a citizen of the United States, residing at Los Angeles, in the county of Los Angeles and State of California, have invented new and useful Improvements in Tables, of which the following is a specification.

My invention is a table and my main object is to provide a table including a detachable rotatable shelf, the parts of which may be folded compactly when the shelf is removed.

Other objects will appear hereinafter.

My invention consists in the features of construction, combination of elements and arrangement of parts which will be herein-after described and pointed out in the claims.

My invention is illustrated in the annexed drawing forming a part of this specification, in which:

Figure 1 is a side elevation of my table, the legs thereof being broken away.

Figure 2 is a cross section of the detachable rotatable shelf taken on line 2—2 of Figure 3.

Figure 3 is a bottom plan of the shelf with the pivot and wheels folded thereupon.

Figure 4 is an enlarged elevation of the shelf pivot and vertical section of the pivot bearing in the table top.

Figure 5 is an enlarged side elevation of the upper portion of the shelf pivot.

Figure 6 is an enlarged elevation of one of the shelf wheel supports.

Figure 7 is an enlarged side elevation of said wheel supports.

The part indicated 1 is the top of the table which is supported on legs 2. In the center of the top of the table is an opening 3 in which is fitted a pivot bearing 4 formed with an upper external flange 5 which is countersunk in the table top and secured thereto by screws 6.

A rotatable shelf 7 which may be circular in shape is detachably mounted upon the table top 1 as will be more particularly described. A shelf pivot 8 includes a T-shaped bracket 9, a bar 10 provided with a longitudinal slot 11, a bar 12 provided with a longitudinal slot 13 and a journal 14. The horizontal arms of the bracket 9 are secured by screws 15 to the under side of the shelf 7 with the vertical member of said bracket depending centrally from the under side of the shelf. The bar 10 is hinged to the lower

end of the depending member of bracket 9 by hinge 16. A screw 17 projects through the slots 11 and 13 in the bars 10 and a butterfly nut 18 screws on the end of said screw. The journal 14 is secured on the lower end of the bar 12 and is adapted to fit and turn in bearing 4, an external flange 19 being formed on the upper end of the journal for engaging the top of the bearing 4. A lock 20 is pivoted to the depending member of the bracket 9 on the side of said member opposite the hinge 16, by a pivot 12, said lock being provided with a slot 22 extending from one edge concentric to said pivot to receive a pin 23 on the upper end of bar 10 to lock said bar and bar 12 in a vertical position.

A plurality of wheels 25, preferably three in number spaced equal distances apart are mounted respectively on a corresponding number of supports 26 secured to the under side of the shelf 7 near the periphery thereof, said wheels resting upon the table top 1 and supporting the shelf so that it may be rotated on the pivot 14 with relation to said top. Each support 26 includes a T-shaped bracket 27 and a bar 28. The horizontal member of the brackets 27 is secured by screws 29 to the under side of the shelf 7 and the upper end of the bar 28 of each support 26 is hinged to the lower end of the depending member of said brackets by a hinge 30. Each bar 28 has a longitudinal slot 31 through which extends an axle 32 on which a wheel 25 is journaled. Each axle has a shoulder 33 which rests against the forward side of a bar 28 and against which rests the rear end of the hub of a wheel 25. The rear end of each axle is threaded and a butterfly nut 34 screws thereon against the rear side of a bar 28. The forward end of each axle 32 is threaded and a nut 35 screws thereon against the forward end of the hub of a wheel 25 to detachably hold the wheel 100 on the axle. A lock 40 is pivoted to the depending vertical member of each bracket 27 on the side of said member opposite the hinge 30 by a pivot 41, said lock being provided with a slot 42 extending from one edge concentric to said pivot to receive a pin 43 extending from the upper end of a bar 28 to lock said bar in a vertical position with the wheel mounted thereon resting upon the table top 1.

In order to rotatably mount the shelf 7 upon the table top 1 the bars 10 and 12 are

swung into a vertical position and locked by the lock 20; the bars 28 are swung into a vertical position and locked by the locks 40; and the shelf 7 is placed over the table 5 top 1 and the journal 14 fitted in the bearing 17 with the wheels 25 resting upon the table top 1. The shelf 7 may then be rotated very easily by hand so that articles on the shelf 7 may be brought within 10 convenient reach of any one at any point of the table, the journal 14 turning in the bearing 4 and the wheels 25 rolling on the table top 1. The shelf may be removed from the table top 1 simply by lifting it off 15 thereof, the journal 14 slipping very readily out of the bearing 4. The pivot 8 and the wheels 25 may be folded upon the under side of the shelf 7 on the hinges 16 and 30 respectively upon disengaging the lock 20 20 from the pin 23 and the locks 40 from the pins 43. The height of the pivot 8 and the distance of the wheels 25 below the shelf 7 may be adjusted by means of the butterfly nuts 18 and 34 respectively to vary 25 the height of the shelf 7 with relation to the table top 1. The individual adjustment of each wheel 25 by means of the butterfly nuts 34 enables the wheels 25 to be adjusted so that all wheels engage the table top 1 30 and support the shelf 7 firmly against rocking or tilting.

I claim:

1. In a table, a bearing in the top thereof, a rotatable shelf, a bracket secured to the 35 under side of said shelf, a swinging pivot member hinged to said bracket, a journal on the lower end of said pivot member adapted to fit detachably in said bearing, a lock pivoted to said bracket provided with a 40 slot, and a pin on the upper end of said swinging pivot member for engaging said slot to hold the pivot swinging member in vertical pivoting position, and means for supporting the shelf in position on the table 45 top.

2. In a table, a shelf, means for detachably pivoting the shelf on the table top, brackets secured to the shelf, a bar hinged to each bracket, a wheel mounted on each bar adapted to rest on the table top to support 50 the shelf, a pin on the upper end of each of said bars, and locks pivotally mounted on said brackets provided with slots to receive said pins to lock said bars in supporting position with the wheels resting upon the 55 table top.

3. In a table, a bearing in the top thereof, a rotatable shelf, a pivot including a pair of longitudinally slotted bars, one of said bars being secured at its upper end to said 60 shelf, a screw extending through the slots of said bars, a butterfly nut screwing onto the end of said screw for adjusting the length of the pivot, a journal on the lower end of the other pivot bar adapted to fit 65 in said bearing, and means for supporting said shelf on the table top.

4. In a table, a shelf, means for pivoting said shelf upon said table, a plurality of slotted bars secured to said shelf, an axle 70 extending through the slot in each of said bars, a shoulder on each axle for engaging the front face of a bar, a butterfly nut screwing on the rear end of each of said axles against the rear face of a bar, and a wheel 75 on each axle adapted to rest on the table top to support the rotatable shelf.

5. In a table, a table top, a rotatable shelf, a series of rollers mounted on said shelf adapted to bear on said table top for supporting 80 said shelf and maintaining it in a horizontal position, a pivot on said shelf detachably engageable with the table top, and members hinged on said shelf on which said pivot and said rollers are mounted 85 adapted to be disposed to extend along the underside of the shelf or to project at substantially right angles thereto.

WILLIAM F. MASON.
